GRILLEWORK FOR TREILLAGE, ROOM DIVIDER OR THE LIKE

Robert F. Seery and John A. Ward, Louisville, Ky., assignors to Julius Blum & Co., Inc., a corporation of
New York

Filed Apr. 10, 1959, Ser. No. 55,447

Term of patent 14 years

(Cl. D54—2)

FIG. 1

FIG. 3

Fig. 1 is an elevational view of a grillework for trellages, room divider or the like, showing our new design, it being understood that the design unit shown has this form throughout.

Fig. 2 is a sectional view taken on line 2—2 of Fig. 1 and

Fig. 3 is a transverse sectional view, taken on line 3—3 of Fig. 1.

We claim:

The ornamental design for a grillework for trellage, room divider, or the like, substantially as shown and described.
